UNITED STATES PATENT OFFICE

CLARENCE L. JOHNSTON, OF BERKELEY, AND EDWARD A. OWENS, OF SAN FRANCISCO, CALIFORNIA, ASSIGNORS TO SELECTASINE SYSTEM, INC., OF SAN FRANCISCO, CALIFORNIA, A CORPORATION OF CALIFORNIA

STENCIL PRINTING MACHINE

Application filed February 10, 1930. Serial No. 427,182.

This invention relates to a stencil printing machine and especially to improvements on the apparatus or machine disclosed in Patent Number 1,687,080, entitled "Method and apparatus for stenciling," and issued to R. C. Beck, October 9, 1928.

In stencil printing, whether by hand or machine operation, a stencil is employed. The stencil comprises a sheet of fabric such as bolting cloth, silk or the like, and this is stretched tightly over a frame. Portions of the fabric are rendered impervious and other portions of the fabric are left open and the open portions are so shaped or arranged as to form the design to be printed. The material to be printed is usually flat sheets of heavy paper, cardboard or the like. The sheets are placed in a flat condition below the stencil. Paint is poured upon the stencil at one end and is uniformly spread and forced through the open portions of the fabric by a scraper or rubber squeegee after which the stencil is raised and the printed sheet removed.

Prior to the development of the machine disclosed in Patent Number 1,687,080, practically all work of this character was accomplished by hand operation and the output of work and quality thereof was largely dependent upon the skill and speed of the operator. Machine stenciling naturally increased the output many times and insured a consistent uniform quality, but practical operation of the machine disclosed several defects and suggested improvements. Such improvements form the basis of the present application and embody a machine capable of greater output and improved quality; a better method of paint transfer and distribution; improved positioning and operation of the stencil; an improved impression cylinder or platen with less tendency to bend or break the sheet of material to be printed upon; improved means for aligning and guiding the sheets; provision of means for dusting or removing foreign matter from the sheets prior to printing thereof; automatic actuated grippers for securing the sheets to the impression cylinder during the printing operation and releasing and discharging the sheets when printed; and further improved

means are provided whereby the squeegee is supported, adjusted and operated so that the pressure exerted upon the stencil fabric and the underlined sheet may be readily adjusted for best results.

The machine is shown by way of illustration in the accompanying drawings, in which—

Fig. 1 is a side elevation showing the side where the feeder or operator stands when the machine is in operation,

Fig. 2 is a plan view of the machine,

Fig. 3 is a side elevation showing the opposite side of the machine,

Fig. 4 is an enlarged side elevation partly broken away to disclose the squeegee operating mechanism,

Fig. 5 is an enlarged side elevation partly broken away showing the cams whereby the squeegee, the paper feed guides and the grippers are operated,

Fig. 6 is a cross section taken on line VI—VI of Fig. 4.

Fig. 7 is a cross section taken on line VII—VII of Fig. 4,

Fig. 8 is an enlarged side elevation in section showing the squeegee mechanism, the paint pan, the sheet grippers, and the sheet feeding guides, and

Fig. 9 is a cross section of the upper portion of the frame showing the manner in which the stencil frame is guided and supported with relation thereto, taken on line IX—IX of Fig. 4.

Referring to the drawings in detail and particularly Figs. 1, 2 and 3, A indicates a base plate on which is mounted a pair of inter-spaced side frames generally indicated at B and C. Journalled crosswise of the frames is a drive shaft 2 which is driven from an electric motor 3 or like source of power through gears 4 and 5. Also journalled crosswise of the frame is a cam shaft 6 which is driven from the drive shaft 2 through the gears indicated at 7 and 8. Secured on the cam shaft are three sets of cams, which are best shown in Figs. 2 and 5. One cam is marked by the numeral 9 and will hereinafter be referred to as the squeegee actuating cam. The second cam is indicated at 10 and will

100

hereinafter be referred to as the gripper actuating cam, and the third cam is indicated at 11 and will be referred to as the paper guide actuating cam. Shaft 6 is continuously driven through the gears 7 and 8. Gear 8 carries a crank pin 12 and three cams 13, 14 and 15. Crank pin 12 serves the function of transmitting an oscillating movement to an impression cylinder or platen generally indicated at 16. The platen presents a curved surface 17 having a large radius. It is counterweighted as indicated at 18 and oscillating movement is transmitted once during each revolution of shaft 6 through a connecting rod 19.

The side frames carry a feeding table 20 upon which the sheets of paper to be printed are stacked. The side frames carry side or guide rails 21 which are angularly disposed as clearly shown in Figs. 1 and 3. The side rails are grooved as indicated at 22 from end to end as shown in Figs. 8 and 9, to receive shoes 23 and hanger arms 24, the hanger arms forming a support for a stencil supporting frame generally indicated at 25. The shoes and hangers are arranged in pairs, one pair at each end of the stencil supporting frame and means are provided whereby a reciprocal movement is transmitted to the stencil supporting frame, the means employed being rack bars 26 secured to each side of the stencil supporting frame and intermeshing segmental gears 26a secured to opposite sides of the platen. Hence during each oscillation of the platen one complete reciprocal motion will be transmitted to the stencil supporting frame and the movement will be unitary and at the same surface speed due to the intermeshing gear segments and racks.

The platen is perhaps best illustrated in Figs. 1 and 8. It is secured on a cross shaft 27 and consists of two side frames 16 and 16a which support the respective segmental gears 26a and a work supporting surface or curved platen 17, see Fig. 7. The frames 16 and 16a are counterweighted as previously stated and indicated at 18 and the counterweights are connected by a cross shaft 19a to which the connecting rod 19 is pivotally secured. The platen carries a number of grippers generally indicated at 29, see Fig. 8, the grippers being normally held in a depressed or gripping position by means of springs 30, each gripper carries a short rack bar 31 and each rack bar intermeshes with a gear 32 secured on a shaft 33 journaled crosswise of the frames 16 and 16a. The springs 30 are secured at their upper ends to the grippers 29 and at their lower ends to a cross shaft or rod 34. Shaft 33 projects through the side frame 16 and carries a crank arm 35 on the outer end of which is secured a roller 36. The roller 36 is adapted to engage a cam 37 formed on one end of an arm 38 which is pivotally secured to the side

frame as at 39, arm 38 being connected with a rod 40, see Figs. 4 and 5, the opposite end of which is connected to a bell crank consisting of two arms indicated at 41 and 42, arm 42 having a roller on its outer end which is adapted to be engaged by the gripper actuating cam 10 once during each revolution of shaft 6. Cam 10 engages arm 42 when the platen assumes its upper or receiving position shown in Figs. 4 and 8, and as such exerts a pull on rod 40 and arm 38 so as to swing cam 38 upwardly against roller 36. This in turn swings the crank arm 35 and shaft 33 in a clockwise direction and as such causes the gears 32 which intermesh with the racks 31 to raise the grippers 29 as shown in Fig. 8, as each sheet of paper or cardboard is advanced from the table 20 to the grippers, the forward edge thereof will be gripped by the grippers a moment prior to movement of the platen in the direction of arrow a as cam 10 will at that moment swing out of engagement with arm 42 and thereby permit reverse movement of the arms 41 and 42 and rod 40, hence lowering the cam 37 and reversing motion of shaft 33, the gears 31 and 32 thereby permitting the springs 30 to pull the grippers downwardly into engagement with a sheet to be printed and as the impression cylinder swings forward the sheet will move with it and a print or impression will be made as will hereinafter be described.

In order that the feeder or operator may have sufficient time to deliver the sheet to the gripping fingers a plurality of guides are employed as indicated at 44, see Figs. 7 and 8, these guides will automatically swing to a depressed position with relation to the surface of the platen 17 the moment the platen has reached its forward or discharging position, hence with the guides depressed it is possible for the operator to feed the next sheet into position during the return movement of the platen. The guides 44 are actuated by the cam 11 through means of rod 45, see Figs. 4 and 5, and a crank arm 46, this arm being secured on a cross shaft 47 to which the guides 44 are adjustably secured as indicated at 48. Cam 11 engages a roller on the lower end of the rod 45 which is fork-shaped as shown in Fig. 5 and the cam moves out of engagement with the roller and rod 45 the moment the impression cylinder reaches discharging position, this permits rod 45 and crank arm 46 to move in the direction of arrow b, see Fig. 4, and the guides are thus depressed or lowered into a position to stop and align the sheet which is fed forwardly by the operator and the sheet is left in this position until the platen is returned to the upper or receiving position shown in Fig. 8, where it is engaged, gripped and removed by the grippers 29 as previously described.

The grippers are raised and the printed

sheet released when the platen reaches its lowermost position by means of a stationary cam indicated at 50, see Fig. 5. Roller 36 secured on crank arm 35 engages this cam 5 when the lowermost position of the platen is reached. Shaft 33 is accordingly rotated and this rotary motion is transmitted through the gears 32 and the rack bars 31 to raise the grippers. A stripping plate 51 extending 10 crosswise of the machine will at the same time enter between the platen and the printed sheet and the moment it has entered it will be rocked in a direction of arrow *c* by means of a rocker arm 52 which is actuated by one 15 or another of the cams indicated at 13, 14 and 15. Rocking movement of the stripping plate 51 raises the forward edge of the sheet above the grippers and thus permits the sheet to fall by gravity onto a conveyor belt 53, 20 which is driven through a sprocket chain 55 from drive shaft 2 and the sheet is thus removed and delivered to a second conveyor 54 when the printing operation is completed. The grippers are released the moment the 25 roller 36 moves out of engagement with the cam 50 and will not be raised again until cam 37 is engaged.

The stencil employed in the present instance is of standard form. It consists of a 30 frame 55 over which is stretched a fabric such as bolting cloth, silk or the like, as indicated at 56 portions of the surface are rendered impervious, for instance, by the application of shellac or other masking materials 35 and other portions are left open, the open portions being so shaped and arranged as to form the design or impression desired during the printing operation. Frame 55 carrying the stencil fabric is secured in the stencil supporting frame 25 in any suitable manner as 40 by quoins such as shown at 55a and it moves in unison with frame 25 and the platen both during the printing and the return operation.

45 The general method of distributing the paint and transferring it through the surface of the stencil is substantially identical to that disclosed in the Beck Patent Number 1,687,080. The stencil is so mounted as to 50 move in one plane, in this instance, on a considerable angle with relation to a horizontal plane. The work or sheet to be printed is deposited on the curved surface of the platen 55 so as to maintain a line of contact between the stencil and the sheet. Means are then 55 provided to-wit, a squeegee for forcing the paint through the open portions of the stencils onto the sheet on said line of contact and the stencil and sheet are moved relatively and 60 in unison so that the line of contact between the stencil and the sheet will be advanced from one end of the sheet to the other. The differences between the mechanism employed in the present instance and that disclosed in 65 the patent previously referred to are, first,

the provision of a segmental shaped platen of large radius so as to reduce any tendency to excessively bend or break the sheet to be printed upon. Secondly, disposing the stencil on an incline and tangent to the surface 70 of the platen; and third, in providing an improved squeegee adjusting and operating mechanism.

The squeegee consists of a rubber blade or scraper generally indicated at 60, see Figs. 6 and 8. It is secured between a pair of plates 61 which are adjustably secured between a pair of guide plates 62, said guide plates being disposed at opposite ends of the plates 61, see Fig. 6. The guide plates are 75 secured at their upper ends to a cross bar 63 which is secured between the outer ends of a pair of crank arms 64. These arms are secured on a shaft 65 which in turn is journaled in bearings mounted on a cross bar 66 80 extending crosswise of the frames B and C and secured thereto by bracket members 67. One end of shaft 65 is extended as shown at 85 68 and a crank arm 69 is secured on the outer end thereof, this crank arm being connected with a rod 70 the lower end of which is connected with a bell crank consisting of arms 71 and 72. The outer end of arm 72 is provided with a roller and this is adapted to be 90 engaged by the cam 9 which has previously 95 been referred to as the squeegee actuating cam. Once during each revolution of shaft 6 cam 9 engages the roller on the outer end of arm 72, a rocking motion is in this manner transmitted to the bell crank comprising 100 the arms 71 and 72 and a pull is exerted on rod 70 and crank arm 69, thus rotating shaft 65 and crank arms 64 in a direction which will swing the outer ends of the crank arms 64 in an upward direction and thereby raise 105 cross bar 63, the guiding brackets 62, the plates 61 adjustably secured therebetween and the squeegee 60. When the cam 9 moves out of engagement with the roller on arm 72 a reverse movement is transmitted and 110 cross bar 63 together with guide brackets 62, plates 61 and squeegee 60 will be lowered into engagement with the surface of the stencil fabric. The lowering movement taking place at the time the stencil screen starts to move downwardly in the inclined guide rails and the platen swings in the direction of arrow *a*. The squeegee remains in this lowered position until the platen reaches its maximum forward or discharge position and 115 the stencil screen has been transversed and reached its lowermost position. At that time cam 9 again engages arm 72 and transmits a reverse motion which raises the squeegee and thereby permits the stencil screen to return and the platen to swing back to receiving position.

120 The squeegee when lowered is maintained in engagement with the stencil surface and the underlying work with a predetermined 125 130

pressure, the pressure being determined by springs 74 and adjusting screws 75, these screws are carried by the upper cross bar 63 and are turnably secured between the plates 61 which support the squeegee plate. By turning the screws 75 and then locking them by the lock nuts as shown it is possible to raise and lower the squeegee plate and the pressure exerted upon the stencil surface and the 10 underlying work may thus be readily regulated to obtain best results. The pressure exerted is, of course, caused by the tension of the springs 74 but as cam 9 and the intermediate connections limit the downward movement any adjustment of screws 75 will 15 vary the pressure exerted.

Operable in conjunction with the squeegee is a paint pan or scoop comprising a plate such as indicated at 78, see Fig. 8. This pan 20 extends from end to end of the squeegee blade and is movable vertically in unison therewith and it is also movable laterally away therefrom. The paint pan is secured to a pair of brackets 79 slidably mounted on 25 rods 80, there being one rod 80 and bracket 79 at each end of the pan 78. The rods 80 are secured in brackets 81 which in turn are secured to the guide brackets 62, see Fig. 6. Springs 82 surround the rods 80 and are 30 interposed between the brackets 79 and 81 and as such tend to move the brackets 79 outwardly against stop collars 83 secured on the rods, such outward movement being cushioned by springs 84. The brackets 79 as previously 35 stated carry the paint pan or scoop 78 and the paint pan and brackets normally assume the position shown in Fig. 8 thereby maintaining the springs 82 in a compressed condition. The brackets 79 are retained in 40 this position by means of a pair of latches 85 pivotally secured to the brackets 81 as indicated at 86. The opposite ends of the latches engage pins 87 on brackets 79 and as such retain the lower edge of the paint pan 45 in engagement with the squeegee blade as shown in Fig. 8. Brackets 79 and 80 are carried by the guide brackets 62 and the paint pan will accordingly move vertically in unison with the squeegee blade when this is 50 raised and lowered. It will however be noted that a pair of cam members are secured to the stencil supporting frame as indicated at 88, one of the cams being shown in Fig. 4. The cams 88 assume the position shown in 55 Fig. 4 when the stencil supporting frame has reached its uppermost position and as such will engage pins 89 secured on the latches 85 when the squeegee is lowered. The latches are thus raised and swung about their pivots 60 86 and as such move out of engagement with the pins 87 on the brackets 79, hence releasing the same and permitting springs 85 to extend and move the brackets 79 together with the paint pan outwardly on the rods 80 against the resilient stop collars 83. Paint

previously deposited in the pan or scoop will thus become deposited on the fabric surface of the stencil and as the stencil moves downwardly in unison with the impression cylinder a certain amount of the paint will be forced through the open portions of the fabric and an impression will be made on the underlying sheet. When the screen has been transversed, or in other words, when it reaches its lowermost position a pair of lugs such as indicated at 91 secured at the upper end of the stencil supporting frame will engage a pair of pins 92 secured to the bracket 79. The brackets will thus be moved inwardly on the rods 80 and as the latches 85 are spring actuated they will ride over and engage the pins 87, thus locking the brackets 79 which carry the paint pan 78 when the paint pan has moved into engagement with the squeegee blade. This movement of the paint pan towards the squeegee blade causes the surplus paint to be scooped up against the surface of the squeegee and as the squeegee will be raised immediately thereafter by the action of the cam 6 the squeegee together with the paint pan and the paint scooped up thereby will be held in an elevated position during the return movement of the stencil and the platen and no paint will be transferred. During the next operation of the stencil and platen the squeegee and the paint pan is lowered the moment the stencil starts downwardly in unison with the platen and the moment the squeegee is lowered latches 85 are released and the paint pan is moved laterally or away from the squeegee so as to deposit the paint on the surface of the stencil thereby permitting transfer thereof through the open portions of the stencil during the impression or printing operation.

All operations so far described are entirely automatic and require no attention on the part of the operator whatsoever, all his attention being directed toward the feeding of the sheets one by one into engagement with the guides indicated at 44. It will of course be understood that he stops and starts the machine whenever necessary, this being accomplished by merely stepping on a foot treadle such as shown at 94. This foot treadle rotates a shaft 95 which in turn actuates a clutch 96 on the main drive shaft. When this clutch is thrown out driving shaft 2 comes to rest and so does the remaining mechanism as all mechanism is operated thereby.

By referring to Figs. 4 and 8, it will be noted that the forward edge of the feeding table is provided with a plurality of forwardly projecting fingers such as indicated at 97. These extend substantially to the point of the grippers and serve the function of maintaining the paper sheets delivered to the guides out of contact with the curved surface of the platen during its return movement.

By referring to Fig. 2, it will be noted that the upper end of the stencil and the sides thereof are permanently blocked out or rendered impervious as indicated by the heavy shade lines at 98. The lower end of the 5 stencil is similarly blocked out but this is not shown. The permanently blocked out surfaces indicated at 98 in actual practice form paint supporting surfaces, the paint being gathered or scooped up on the surface 98 at the upper end of the stencil and being deposited on the lower blocked out surface 98 prior to transfer through the open surfaces of the stencil. The inclined position of the 10 stencil is important. This is best shown in Figs. 4 and 8. Such inclination causes any surplus paint to run towards the squeegee or scraper 60 and as such is always gathered up by the paint pan or scoop during each scooping 15 operation.

While certain features of the present invention are more or less specifically described, we wish it understood that various changes may be resorted to within the scope of the 20 appended claims. Similarly, that the materials and finishes of the several parts employed may be such as the manufacturer may decide, or varying conditions or uses may demand.

Having thus described our invention, what we claim and desire to secure by Letters Patent is—

1. In a machine of the character described, a curved platen, a stencil, means disposing 35 the stencil on an angle with relation to a horizontal plane and on a tangent to the surface of the platen, means for introducing material to be printed between the stencil and the platen, grippers on the platen for holding 40 the material in engagement with the surface of the platen, means whereby an oscillating movement is transmitted to the platen and a simultaneous reciprocal movement to the 45 stencil so that a rolling contact will be made between the material to be printed and the surface of the stencil, and means for forcing 50 pigment through the stencil on the line of contact between the stencil and the material.

2. In a machine of the character described, 55 a segmental shaped platen, a stencil spaced from the platen, means disposing the stencil on an angle with relation to a horizontal plane and on a tangent to the surface of the platen, means for introducing material to be 60 printed between the stencil and the platen, grippers on the platen for maintaining the material in engagement with the surface of the platen, means whereby an oscillating movement is transmitted to the platen 65 and a simultaneous reciprocal movement to the stencil so that a rolling contact will be made between the material to be printed and the surface of the stencil, a scraper vertically disposed with relation to a horizontal plane 70 and angularly disposed with relation to the

surface of the stencil, and means whereby the scraper is moved into engagement with the stencil so as to bring a line of the stencil surface into engagement with the material to be printed.

3. In a machine of the character described, a segmental shaped platen, a stencil spaced from the platen, means disposing the stencil on an angle with relation to a horizontal plane and on a tangent to the surface of the platen, means for introducing material to be printed between the stencil and the platen, grippers on the platen for maintaining the material in engagement with the surface of the platen, means whereby an oscillating movement is transmitted to the platen and a simultaneous reciprocal movement to the 75 stencil so that a rolling contact will be made between the material to be printed and the surface of the stencil, a squeegee vertically disposed with relation to a horizontal plane and angularly disposed with relation to the surface of the stencil, means whereby the squeegee is moved into engagement with the surface of the stencil, and means for regulating the pressure exerted by the squeegee on the stencil and the underlying material to be 80 printed.

4. In a machine of the character described, a segmental shaped platen, a stencil spaced from the platen, means disposing the stencil on an angle with relation to a horizontal plane and on a tangent to the surface of the platen, means for introducing material to be printed between the stencil and the platen, grippers on the platen for maintaining the material in engagement with the surface of the platen, means whereby an oscillating movement is transmitted to the platen and a simultaneous reciprocal movement to the 90 stencil so that a rolling contact will be made between the material to be printed and the surface of the stencil, a scraper vertically disposed with relation to a horizontal plane and angularly disposed with relation to the surface of the stencil, means whereby the scraper is moved into engagement with the surface of the stencil, and means for maintaining a 95 supply of pigment on the surface of the stencil and adjacent one side of the scraper.

5. In a machine of the character described, a segmental shaped platen, a stencil spaced from the platen, means disposing the stencil on an angle with relation to a horizontal plane and on a tangent to the surface of the platen, means for introducing material to be printed between the stencil and the platen, grippers on the platen for maintaining the material in engagement with the surface of the platen, means whereby an oscillating movement is transmitted to the platen and a simultaneous reciprocal movement to the 100 stencil so that a rolling contact will be made between the material to be printed and the surface of the stencil, a scraper vertically disposed with relation to a horizontal plane and angularly disposed with relation to the surface of the stencil, means whereby the scraper is moved into engagement with the surface of the stencil, and means for maintaining a 105 supply of pigment on the surface of the stencil and adjacent one side of the scraper.

110

5. In a machine of the character described, a segmental shaped platen, a stencil spaced from the platen, means disposing the stencil on an angle with relation to a horizontal plane and on a tangent to the surface of the platen, means for introducing material to be printed between the stencil and the platen, grippers on the platen for maintaining the material in engagement with the surface of the platen, means whereby an oscillating movement is transmitted to the platen and a simultaneous reciprocal movement to the 120 stencil so that a rolling contact will be made between the material to be printed and the surface of the stencil, a scraper vertically disposed with relation to a horizontal plane and angularly disposed with relation to the surface of the stencil, means whereby the scraper is moved into engagement with the surface of the stencil, and means for maintaining a 125 supply of pigment on the surface of the stencil and adjacent one side of the scraper.

130

disposed with relation to a horizontal plane and angularly disposed with relation to the surface of the stencil, means whereby the scraper is moved into engagement with the 5 surface of the stencil, means for maintaining a supply of pigment on the surface of the stencil and at one side of the scraper while the scraper is maintained in engagement with the surface of the stencil, and means for removing 10 the supply of pigment from the surface of the stencil when the scraper is moved away from the surface of the stencil.

6. In a machine of the character described, a segmental shaped platen, a stencil spaced 15 from the platen, means disposing the stencil on an angle with relation to a horizontal plane and on a tangent to the surface of the platen, means for introducing material to be printed between the stencil and the platen, 20 grippers on the platen for maintaining the material in engagement with the surface of the platen, means whereby an oscillating movement is transmitted to the platen and a simultaneous reciprocal movement to the 25 stencil so that a rolling contact will be made between the material to be printed and the surface of the stencil, a scraper vertically disposed with relation to a horizontal plane and angularly disposed with relation to the 30 surface of the stencil, means whereby the scraper is moved into engagement with the surface of the stencil, a paint pan disposed adjacent one side of the scraper and containing a supply of pigment, means for lowering the paint 35 pan in unison with the scraper and for imparting lateral movement to the paint pan away from the scraper so as to deposit the pigment on the surface of the stencil while the scraper is maintained in engagement 40 therewith, and means for moving the paint pan toward the scraper and for elevating it in unison with the scraper when the scraper is moved away from the surface of the stencil so as to remove the pigment from the surface 45 of the stencil.

7. In a machine of the character described, the combination with the platen and means for transmitting an oscillating movement thereto, of a plurality of grippers projecting 50 through the surface of the platen, said platen adapted to assume a receiving position and a discharging position, means whereby the grippers are automatically elevated when the platen resumes a receiving position, said 55 means automatically causing depression of the grippers prior to movement of the platen toward discharging position, other means whereby the grippers are automatically elevated when the platen reaches discharging 60 position, and a plurality of guide members co-operating with the grippers.

8. In a machine of the character described, the combination with the platen and means for transmitting an oscillating movement 65 thereto, of a plurality of grippers project-

ing through the surface of a platen, said platen adapted to assume a receiving position and a discharging position, means whereby the grippers are automatically elevated when the platen resumes a receiving position, 70 said means automatically causing depression of the grippers prior to movement of the platen toward discharging position, other means whereby the grippers are automatically elevated when the platen reaches discharging 75 position, a plurality of guide members co-operating with the grippers, and means whereby the guide members are automatically depressed during movement of the platen from discharging toward receiving position, 80 said means automatically elevating the guide members prior to movement of the platen from receiving to discharging position.

9. In a machine of the character described, a platen, a plurality of grippers projecting 85 through the face thereof, a rack bar on each gripper, a cross shaft journaled in the platen, a plurality of gears secured on said shaft and intermeshing with the rack bars of the grippers, a crank arm on the shaft, means 90 for transmitting an oscillating movement to the platen, said platen assuming a receiving position and a discharging position during oscillation thereof, and a stationary cam engageable with the crank arm when the platen reaches a discharging position and imparting an oscillating movement to the cross shaft and gears so as to transmit elevating movement 95 to the rack bars and the grippers actuated thereby.

10. In a machine of the character described, a platen, a plurality of grippers projecting through the face thereof, a rack bar on each gripper, a cross shaft journaled in the platen, a plurality of gears secured on said shaft and intermeshing with the rack bars of the grippers, a crank arm on the shaft, means for transmitting an oscillating movement to the platen, said platen assuming a receiving position and a discharging position during 105 oscillation thereof, stationary cam engageable with the crank arm when the platen reaches a discharging position and imparting an oscillating movement to the cross shaft and gears so as to transmit elevating movement 110 to the rack bars and the grippers actuated thereby, and a movable cam engageable with the crank arm as the platen approaches receiving position, said cam causing elevation 115 of the grippers as the platen reaches receiving position and causing depression of the grippers prior to movement of the platen from receiving to discharging position.

11. In a machine of the character described, a platen mounted for oscillating movement, 120 guide members co-operating therewith, and automatically actuated means maintaining the guide members in substantial contact with the surface of the platen during movement in one direction, said means automatically ele- 125

vating the guide members during movement of the platen in an opposite direction.

12. In a machine of the character described, a platen adapted to be oscillated and movable during oscillation from a receiving to a discharging position, a plurality of grippers on the platen and adapted to grip and secure material fed thereto when the platen assumes a receiving position, means whereby the grippers are moved to release the material prior to the platen reaching discharging position, a stripper plate adapted to be introduced between the surface of the platen and the material, and means for transmitting an oscillating movement to the stripper plate to raise the material above the grippers and to assist gravity discharge of the material with relation to the platen.

13. In a machine of the character described, a platen, a stencil co-operating therewith, a squeegee and paint delivering mechanism co-operating with the stencil, grippers mounted on the platen, a driving shaft, means on said shaft whereby an oscillating movement is transmitted to the platen and a simultaneous reciprocal movement to the stencil, a plurality of cams on the drive shaft, and means whereby said cams automatically actuate the grippers and the squeegee together with the paint delivery mechanism.

14. In a machine of the character described, a platen, a stencil co-operating therewith, a squeegee and paint delivering mechanism co-operating with the stencil, grippers mounted on the platen, a driving shaft, means on said shaft whereby an oscillating movement is transmitted to the platen and a simultaneous reciprocal movement to the stencil, a plurality of cams on the drive shaft, means whereby said cams automatically actuate the grippers and the squeegee together with the paint delivery mechanism, and a stationary cam whereby the grippers are intermittently actuated independently of said first named means.

15. In a machine of the character described, a platen, a stencil co-operating therewith, a squeegee and paint delivering mechanism co-operating with the stencil, grippers mounted on the platen, a driving shaft, means on said shaft whereby an oscillating movement is transmitted to the platen and a simultaneous reciprocal movement to the stencil, a plurality of cams on the drive shaft, means whereby said cams automatically actuate the grippers and the squeegee together with the paint delivery mechanism, a stationary cam whereby the grippers are intermittently actuated independently of said first named means, a stripping plate disposed adjacent the stationary cam, and a plurality of cams on the drive shaft whereby an oscillating movement is transmitted to the stripping plate.

16. In a machine of the character described, a platen, a stencil co-operating therewith, a

squeegee and paint delivering mechanism co-operating with the stencil, grippers mounted on the platen, a driving shaft, means on said shaft whereby an oscillating movement is transmitted to the platen and a simultaneous reciprocal movement to the stencil, a plurality of cams on the drive shaft, means whereby said cams automatically actuate the grippers and the squeegee together with the paint delivery mechanism, a stationary cam whereby the grippers are intermittently actuated independently of said first named means, a stripping plate disposed adjacent the stationary cam, a plurality of cams on the drive shaft whereby an oscillating movement is transmitted to the stripping plate, guide members co-operating with the grippers, and a cam on the drive shaft whereby the guide members are automatically raised and lowered with relation to the surface of the platen.

17. In a machine of the character described, a stationary frame, a squeegee, a frame supporting the squeegee and vertically movable in the stationary frame, a paint pan supported by the squeegee frame and vertically movable in unison therewith, a stencil frame reciprocally mounted below the squeegee, means whereby reciprocal movement of the stencil frame in one direction is transmitted to move the paint pan towards the squeegee and into engagement therewith, means automatically engaging the pan and securing it with relation to the squeegee and its frame, spring means engaged by the pan and adapted to be compressed during movement of the paint pan towards the squeegee, and means actuated by reciprocal movement of the stencil in an opposite direction for releasing the pan to permit the spring means to move the pan away from the squeegee.

18. In a machine of the character described, a stationary frame, a squeegee, a frame supporting the squeegee and vertically movable in the stationary frame, a pair of rods secured to the squeegee frame, a paint pan slidably mounted on the rods and movable into and out of engagement with the squeegee, springs on the rods and engageable with the pan and normally maintaining the pan out of engagement with the squeegee, a stencil reciprocally mounted below the squeegee, means whereby reciprocal movement of the stencil in one direction is transmitted to move the paint pan into engagement with the squeegee, a latch pivotally mounted on the squeegee frame and engageable with the pan to secure it when in engagement with the squeegee, and a cam carried by the stencil and engageable with the latch to release the same during reverse movement of the stencil to permit the springs to move the pan out of engagement with the squeegee.

19. In a machine of the character described, a segmental shaped platen, a feed table disposed adjacent the same, a plurality

of guide members disposed above the feed table and the platen and movable to and away from the surface of the platen, said platen adapted to assume a receiving position and a discharging position, automatically actuated means transmitting movement to depress the guide members during movement of the platen from discharge to receiving position, a plurality of fingers on the feed table and 10 extending from the forward edge of the feed table to the guide members, said fingers maintaining a paper sheet moved into register with the guide members from engaging the surface of the platen during movement thereof from discharging to receiving position.

20. In a machine of the character described, a segmental shaped platen, a feed table disposed adjacent the same, a plurality of guide members disposed above the feed table and the platen and movable to and away from the surface of the platen, said platen adapted to assume a receiving position and a discharging position, automatically actuated means transmitting movement to 25 depress the guide members during movement of the platen from discharge to receiving position, a plurality of fingers on the feed table and extending from the forward edge of the feed table to the guide members, said fingers maintaining a paper sheet moved into register with the guide members from engaging the surface of the platen during movement thereof from discharging to receiving position, a plurality of grippers carried by 30 the platen and engageable with the paper sheet supported by the fingers and held by the guide members, means automatically raising the guide members away from the platen when the grippers move into engagement 35 with the paper sheet, and means automatically depressing the grippers into gripping engagement with the paper sheet substantially simultaneous with raising of the guide members.

40. 21. In a machine of the character described, a segmental shaped platen, a feed table disposed adjacent the same, a plurality of guide members disposed above the feed table and the platen and movable to and away from the surface of the platen, said platen adapted to assume a receiving position and a discharging position, automatically actuated means transmitting movement to depress the guide members during movement of the 45 platen from discharge to receiving position, a plurality of fingers on the feed table and extending from the forward edge of the feed table to the guide members, said fingers maintaining a paper sheet moved into register with the guide members from engaging the surface of the platen during movement thereof from discharging to receiving position, a plurality of grippers carried by the platen and engageable with the paper sheet supported by the fingers and held by the guide members, means automatically raising the guide members away from the platen when the grippers move into engagement with the paper sheet, means automatically depressing the grippers into gripping engagement with the paper sheet substantially simultaneous with raising of the guide members. said grippers securing the forward edge of the paper sheet with relation to the 50 curved surface of the platen, and rollers engageable with the sheet of paper and maintaining it in contact with the curved surface of the platen during movement of the platen from receiving to discharging position.

55. CLARENCE L. JOHNSTON
EDWARD A. OWENS.

members, means automatically raising the guide members away from the platen when the grippers move into engagement with the paper sheet, means automatically depressing the grippers into gripping engagement 70 with the paper sheet substantially simultaneous with raising of the guide members, said grippers securing the forward edge of the paper sheet with relation to the curved surface of the platen, and other means engageable with the sheet of paper and maintaining the remaining portion of the sheet in engagement with a curved surface of the platen during movement of the platen from receiving to discharging position.

22. In a machine of the character described, a segmental shaped platen, a feed table disposed adjacent the same, a plurality of guide members disposed above the feed table and the platen and movable to and away from the surface of the platen, said platen adapted to assume a receiving position and a discharging position, automatically actuated means transmitting movement to depress the guide members during movement of the 80 platen from discharge to receiving position, a plurality of fingers on the feed table and extending from the forward edge of the feed table to the guide members, said fingers maintaining a paper sheet moved into register with the guide members from engaging the surface of the platen during movement thereof from discharging to receiving position, a plurality of grippers carried by the platen and engageable with the paper sheet supported by the fingers and held by the guide members, means automatically raising the guide members away from the platen when the grippers move into engagement with the paper sheet, means automatically depressing the grippers into gripping engagement with the paper sheet substantially simultaneous with raising of the guide members. said grippers securing the forward edge of the paper sheet with relation to the 85 curved surface of the platen, and rollers engageable with the sheet of paper and maintaining it in contact with the curved surface of the platen during movement of the platen from receiving to discharging position.
